[57] CLAIM

The ornamental design for a night depository for use with an automated teller machine or similar article, as shown and described.

DESCRIPTION

FIG. 1 is a front elevational view of a night depository for use with an automated teller machine or similar article showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a top, front and right side perspective view thereof; and

FIG. 7 is a top, front and right side perspective view similar to FIG. 6 wherein the broken line showing of an automated teller machine is illustrative of environmental structure only and forms no part of the claimed design.

The bottom of the claimed design is flat and unornamented.

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 314,076

DATED : January 22, 1991

INVENTOR(S) : Alex M. Tarkany et al.

It is certified that error appears in the above-identified patent and that said Letters Patent is hereby corrected as shown below:

On the title page:

Include as inventor for [75] Melvin L. Walter,
513 Audubon Village Spur, Grover, MO 63040.

Signed and Sealed this
Fifth Day of January, 1993

Attest:

DOUGLAS B. COMER

Attesting Officer

Acting Commissioner of Patents and Trademarks

UNITED STATES PATENT AND TRADEMARK OFFICE
CERTIFICATE OF CORRECTION

PATENT NO. : Des. 314,076
